UNITED STATES PATENT OFFICE.

HEINRICH TRAUN, OF HAMBURG, GERMANY.

DESIGN FOR A SIGN.

SPECIFICATION forming part of Design No. 22,006, dated November 22, 1892.

Application filed September 13, 1892. Serial No. 445,807. Term of patent 7 years.

To all whom it may concern:

Be it known that I, HEINRICH TRAUN, a subject of the Emperor of Germany, and a resident of Hamburg, Germany, have invented a certain new and original Design for Signs, of which the following is a specification.

This invention relates to a design for signs, the leading feature of which consists in a sign having the outlines of a hair-comb, the body of the sign being provided with a number of parallel vertical shallow depressions alternating with raised portions in conventional representation of the teeth of the comb.

The nature of my design is fully shown in the accompanying drawings, in which—

Figure 1 is a side elevation of the sign, and Fig. 2 a vertical transverse section on the line 2 2, Fig. 1.

Similar letters of reference indicate corresponding parts.

A represents a sign, the outlines of which

are made in the shape of a hair-comb. In the body of the sign are arranged parallel depressions *a*, which alternate with the raised portion *d*, one half of the body being provided with wider depressions *a* and the other half being provided with narrower depressions *b*. The depressions *a* and *b*, alternating with the intermediate raised portion *d*, impart the conventional representation of the teeth of a comb to the design for a sign.

I claim—

The design for a sign, substantially as herein shown and described.

In testimony that I claim the foregoing as my invention I have signed my name in presence of two subscribing witnesses.

HEINRICH TRAUN.
